Primary Examiner — Cynthia Ramirez*Assistant Examiner* — Jeremy S. Swartz(57) **CLAIM**

The ornamental design for a self pushing beverage organizer, as shown and described.

DESCRIPTION

FIG. 1 is a front and top perspective view of a self pushing beverage organizer design showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is another perspective view thereof, shown in an alternate position.

The broken lines in the drawings depict portions of the self pushing beverage organizer that form no part of the claimed design.

1 Claim, 8 Drawing Sheets(56)
